EX

OF D 13,478

Design No. 13,478, dated December 12, 1882.

UNITED STATES PATENT OFFICE.

HENRY J. SCHMEHL, OF BOSTON, MASSACHUSETTS, ASSIGNOR TO CHARLES G. PEASE, OF SAME PLACE.

DESIGN FOR A CHAIR.

SPECIFICATION forming part of Design No. 13,478, dated December 12, 1882.

Application filed October 30, 1882. Term of patent 14 years.

To all whom it may concern:

Be it known that I, HENRY J. SCHMEHL, of Boston, in the county of Suffolk and State of Massachusetts, have invented a new and original Design for Chairs, of which the following is a specification.

My design relates to chairs having a frame-work covered by strands of rattan, reed, or other like fibrous material wound upon the frame-work so as to conceal the latter, excepting the seat-frame. Heretofore each piece or component part of the frame-work, excepting the seat-frame, has been covered by a single strand wound around the piece, each coil of the strand abutting against the next, so that the pitch or degree of the spiral produced by such winding is hardly perceptible, and the wound strand has more the effect of a series of independent bands or wings than a continuous spirally-wound strand.

My design involves the employment of several fibrous strands laid side by side, instead of one, as heretofore, the strands, when wound spirally, having a much greater pitch or obliquity than a single strand, and giving the parts covered a rope-like effect, which is the chief feature of my design, as I will now proceed to describe.

The nature of my design is fully set forth in the accompanying photographic illustration, forming a part of this specification, and representing a perspective view of a chair.

In said illustration, A A represent the parts of the chair-frame which are wound with strips

of rattan, or rattan-pith, or reed, to resemble 35 a rope, a number of strands being employed for each part of the frame, and laid side by side, so that when wound they will necessarily have a more oblique or rapid twist or spiral than a single strand, and will therefore give the 40 parts covered the rope-like effect shown. A novel and ornamental appearance is thus imparted to the chair.

I do not limit myself to covering the entire frame-work in the manner described, nor to 45 the application of my design to any particular style of chair.

The two parts of the frame-work that constitute the outer sides of the back are preferably provided at their upper ends with caps 50 B B, composed of fibrous strands woven into basket-work.

I claim—

1. The design for a chair having a part or parts of its frame wound with strands to resemble ropes, substantially as shown and described.

2. The design for a chair having the basket-work caps B B, substantially as shown and described.

In testimony whereof I have signed my name to this specification, in the presence of two subscribing witnesses, this 13th day of June, 1882.

HENRY J. SCHMEHL.
